(57) **CLAIM**

The ornamental design for a wireless charger for headset, as shown and described.

DESCRIPTION

FIG. 1 is a perspective view of a wireless charger for headset showing our new design;
FIG. 2 is a front view thereof;
FIG. 3 is a rear view thereof;
FIG. 4 is a left side view thereof where the right side view is a mirror image;
FIG. 5 is a top plan view thereof;
FIG. 6 is a bottom plan view thereof; and,
FIG. 7 is a reference view thereof showing the way of the headset being attached to the subject design.
The broken lines in FIG. 7 show environmental structure only and form no part of the claimed design.
